UNITED STATES PATENT OFFICE.

EMMETT CLIFFORD DAVEY, OF MANKATO, MINNESOTA, ASSIGNOR OF ONE-FOURTH TO
HARRY W. BAKER, OF MANKATO, MINNESOTA.

ELECTRIC PIPE-THAWING APPARATUS.

1,289,686.

Specification of Letters Patent.

Patented Dec. 31, 1918.

Application filed July 26, 1918. Serial No. 246,902.

To all whom it may concern:

Be it known that I, EMMETT CLIFFORD DAVEY, a citizen of the United States, residing at Mankato, in the county of Blue Earth 5 and State of Minnesota, have invented new and useful Improvements in Electric Pipe-Thawing Apparatus, of which the following is a specification.

This invention is an improved electric apparatus for use in thawing frozen water pipes under ground, the object of the invention being to provide an improved apparatus of this kind which can be operated by current of ordinary voltage, as for instance, from the ordinary 110 volt lighting circuit, and which permits bare copper wire to be used to connect to the pipes and to be laid across streets without danger of animals or pedestrians passing over the same.

With the above and other objects in view, the invention consists in the construction, combination and arrangement of devices hereinafter described and claimed.

In the accompanying drawings:

Figure 1 is a plan, partly in section, of an electric thawing apparatus constructed and arranged in accordance with my invention.

Fig. 2 is a detail sectional view of the same.

Fig. 3 is a detail perspective view showing the construction of the core.

Fig. 4 is a perspective view of the same with the container indicated in dotted outline.

In the embodiment of my invention, I provide an induction coil 1. The core 2 of the coil comprises laminae 3 of silicon steel which, in practice, are 17/100 of an inch in thickness and which are arranged in alternation and in overlapping relation at the corners of the core, thus forming side members 4 and end members 5 of the core and, in practice, a large number of such laminae, usually about 690, are employed in the making of the core. There are two sets 6, 7 of

primary windings on the core each consisting, in practice, of about 124 turns of No. 10 double cotton covered magnet wire wound in four layers; that is to say, two layers on each leg of the core with necessary insulation 8 between the layers. The primary windings 6, 7 are respectively provided with leads 9, 10 which connect the primary windings to the source of current. The secondary windings 11 are, in practice, composed

of three No. 5 double cotton covered magnet wires wound in multiple and consisting of five turns to each leg of the core. These secondary windings are connected by leads 12 to the pipes to be thawed.

The induction coil is arranged in a container 13 which is made of iron and the top, bottom, side and end walls of which are corrugated, as shown.

The corrugations increase the superficial area of the container and provide a maximum cooling surface. The bottom of the container is provided near the corners with raised bosses 14. The laminae of the core are clamped and held together by lower and upper bars 15, 16 which are arranged across the ends of the core and are connected together by bolts 17 the lower ends of which are threaded in the bosses 14. Clamping nuts 18 bear on and securely hold the upper bars 16. The upper portions of the bolts extend through openings in the top 19 of the container and securing nuts 20 are screwed on the upper ends of the bolts and bear on the top of the container and hold the same in securely closed position. The container is filled with oil to prevent overheating and also to insure better insulation.

By the provision of the two sets of primary windings the apparatus is adapted to be operated by electric current of different voltages. The leads 9, 10 enable the primary windings to be connected to conductors charged with current at either 110 or 220 volts. 220 volts should only be used on long runs and for not more than about 1 hour on account of heating. 110 volts may be used on either of the primary windings indefinitely without any harmful effects occasioned by heating.

First locate freeze as nearly as possible. Connect one secondary wire at one end of pipe, and the other secondary wire on other end, making a circuit as short as possible. This will thaw out the pipe between points connected.

In cases where, what is known as the service main leading from the building to the main, is frozen, the connection is made through the shut-off.

Silicon steel is used in the apparatus to secure greater permeability. The current passes through the circuit which is formed causing the frozen portion to thaw, and the same holds of frozen gas pipes.

Having thus described my invention, I claim:—

1. An electric thawing apparatus comprising an induction coil having a core composed of superposed members, cross bars on opposite sides of the core, a container in which the induction coil is arranged, said container having a removable cover, and bolts extending through the cross bars, and through the cover of the container and provided with means to clamp the cross bars on the core and to also secure the coil and the cover in place.
2. In electric thawing apparatus of the class described, a container having a remov-

able cover, an induction coil arranged in the container and having a core composed of laminæ of silicon steel arranged in alternating and partially overlapping relation, cross bars extending across the ends of the core and between which the laminæ are arranged and bolts extending through said cross bars and clamping the core laminæ therebetween, the said bolts being attached to the bottom of the container and extending through the openings in the cover thereof and clamping nuts on the bolts bearing on the cover and also securing the latter in place.

In testimony whereof I affix my signature.
EMMETT CLIFFORD DAVEY.
